UNITED STATES PATENT OFFICE.

SAMUEL B. SHELDON, OF DULUTH, MINNESOTA.

GAS-PRODUCER.

1,350,474.

Specification of Letters Patent.

Patented Aug. 24, 1920.

Application filed September 6, 1918. Serial No. 252,862.

To all whom it may concern:

Be it known that I, SAMUEL B. SHELDON, a citizen of the United States, residing at Duluth, in the county of St. Louis and State of Minnesota, have invented certain new and useful Improvements in Gas-Producers, of which the following is a specification.

This invention relates to gas producers.

One of the objects of this invention is to relieve the gas producer top of strains incident to heavy loads placed thereon.

Another object is to provide a gas producer, the operating parts of which are arranged in a manner to facilitate repair of such parts.

Another object is to provide a simple and efficient top construction for gas producers adapted to meet the various requirements for successful commercial operation.

These and other objects are accomplished by means of the mechanism shown by the accompanying sheets of drawings, in which—

Figure 1 is a plan view of a gas producer embodying my invention, and

Fig. 2 is a fragmentary vertical sectional view of the same gas producer.

The various novel features of my invention will be apparent from the following description and drawings, and will be particularly pointed out in the appended claims.

Referring to the figures of the drawings, it will be noted that I have provided a gas producer having a main body portion 10, a top 11 therefor, and a superstructure 12 carrying the operating mechanism, said operating mechanism and superstructure being mounted over the top 11 and supported independently thereof.

The stationary track 13 forming a part of the body portion 10, has formed integrally therewith an annular channel portion 14, in which a vertical flange 15 of the top 11 rotates, there being water in the channel portion 14 above the lower extremity of the vertical flange 15, forming a seal against the passage of gas from the inside to the outside of the producer. Secured to the producer top 11 and extending through openings 16 therein are seal members 17 which extend downwardly into the gas producer, said members having flanges 18 which surround vertical flanges 19 on the producer top to form seals against the escape of producer gas, it being understood that a sup-

ply of water is maintained on top of the gas producer top 11. Extending through the hollow vertical leg 20 of the seals 17 are the shanks 21 of the pokers 22, which are operatively connected to a walking beam 23 mounted upon a shaft 24, which is actuated through an operating member 25, which may receive movement from any suitable source.

The shaft 24 is mounted in bearing members 26, carried by cross beams 27, which are connected to and supported by main beams 28 forming the main part of the superstructure for supporting the operating mechanism. The walking beam is connected to the shanks 21 of the pokers, preferably in a manner as shown in my copending application, Serial No. 239,861, filed June 11, 1918, by means of which the pokers are positively raised, but permitted to lower into the fuel bed in accordance with their own weight for maintaining the fuel bed in a uniformly porous condition. It will be noted that the pokers are located at different distances from the center of the gas producer, whereby upon a complete rotation of the gas producer top and superstructure all of the fuel will be treated. The supporting superstructure 12 is provided at its four corners with depending members having bearings 26 for the reception of shafts, at the outer ends of which are mounted carrying wheels 27 which roll on the track 13.

The motor 28 for actuating the pokers and rotating the superstructure 12 and the top 11 is mounted upon the superstructure, and is provided with a shaft 29, one end of which is provided with a pinion 30 meshing with a relatively large gear 31 mounted upon a shaft 32 extending into a gear box 33. Extending from the gear box is an operating connection to the member 25 for actuating the walking beam 23, and also extending from said gear box 33 is a shaft 34 carrying at one end a pulley or gear 35, around which passes a flexible connection 36, which also passes around a relatively large pulley or gear 37 mounted upon one end of a shaft 38, which is mounted in bearings 39 carried by the producer top 11. At the outer end of the shaft is a propelling wheel 40 which also rides upon the track 13.

The top 11 also has other carrying wheels 42. Through this driving connection the top and the superstructure are rotated on the stationary body portion 10, it being

understood that the superstructure 12 and the top 11 are rigidly connected by any suitable frame connection 41.

By means of this arrangement the producer top 11, which of necessity is a casting of relatively large diameter, is relieved of strains incident to the load of the mechanism which must be mounted thereover. Furthermore, by means of this arrangement, it is a relatively simple matter to repair the mechanism, or to replace the top if such becomes necessary. If desired, the wheels supporting the producer top 11, and those supporting the superstructure, may 15 operate on different tracks.

There also may be various other modifications of the invention herein particularly shown and described, and it is my intention to cover all such modifications which do not 20 involve a departure from the spirit and scope of the following claim.

What I claim is:

In a gas producer, the combination of a main body portion having a track thereon, a rotary top for the producer, a rotatably mounted superstructure mounted over said top and supported independently thereof, producer operating mechanism mounted on said superstructure, and propelling means mounted on said superstructure for driving said operating mechanism and for rotating said top and superstructure, the rotary top and superstructure being supported directly on said main body portion, and movably mounted on said track. 25 30 35

Signed at Duluth, Minnesota, this 19th day of August, 1918.

SAMUEL B. SHELDON.
